UNITED STATES PATENT OFFICE.

WILLIAM T. HILDRUP, JR., OF HARRISBURG, PENNSYLVANIA.

BOILER-SETTING.

SPECIFICATION forming part of Letters Patent No. 298,380, dated May 13, 1884.

Application filed September 26, 1883. (No model.)

To all whom it may concern:

Be it known that I, WILLIAM T. HILDRUP, Jr., a citizen of the United States, residing at Harrisburg, Pennsylvania, have invented new 5 and useful Improvements in Boiler-Settings, of which the following is a specification.

My invention relates to certain new and useful improvements in boiler-settings. It has for its object to provide a means for feeding 10 shavings, sawdust, spent bark, &c., to the fire-box directly at the front and in such manner that cold drafts will not strike the heated boiler-sheets. It has also for its object to so 15 construct and arrange the grate-bars as to provide for a sufficient supply of air, and at the same time secure the bars against warping by heat. It has also for its object to provide a specially-constructed hot-air flue in the fire-bridge; and with these ends in view my in- 20 vention consists in the peculiar construction and arrangement of parts hereinafter fully described and specifically claimed.

In order that those skilled in the art to which 25 my invention appertains may know how to make and use the same, I will proceed to describe the construction and operation, referring by letters to the accompanying drawings, in which—

Figure 1 is a longitudinal section showing 30 my improved settings. Fig. 2 is a front elevation. Fig. 3 is a side and front elevation and plan of step-bar supports. Fig. 4 is a plan view of the grate-bars; Fig. 5, a side elevation of the same; Fig. 6, a cross-section on line 35 $x x$; Fig. 7, a similar section at $y y$. Fig. 8 is a plan view of the heating-flue-bridge casting. Fig. 9 is a section at line $z z$, Fig. 8. Fig. 10 is a front elevation and section of damper-box for hot-air flue, and Fig. 11 is a similar view 40 of damper.

Similar letters indicate like parts in the several figures.

All parts not specially referred to are of such construction and arrangement as is usual 45 in boiler-settings, my invention relating only to the construction and arrangement of the feed-hopper, stepped grates, and fire-bridge flue.

A represents a fuel-hopper, which is ar- 50 ranged at the front end of the fire-box, the upper edge of the said hopper extending above the throat or opening B, between two castings

or cross-beams, C D, which are built into and are flush with the faces of the side walls, which support the boiler. Upon these castings are 55 two pilaster-plates, E F, Figs. 1 and 2, which are anchored in place by suitable rods, built in the side walls. The pilaster-plates E F are formed integral with the furnace-frame, and are formed with projections G on their sides next 60 to the boiler, extending outwardly and at right angles to the front face of the walls forming the ends of the hopper, and to these projections are riveted or bolted strips of iron, H, upon which rests a plate, I, which forms the front of 65 the hopper. The front plate of the hopper is, as will be observed by reference to Fig. 1, inclined, so that the fuel will gravitate to the fire-box, and the height of the hopper above the throat B is such that when the contents of 70 the hopper extend above the bottom of the cross-beam or casting C the throat B is effectively closed against the ingress of any cold drafts of air, and the hot boiler-sheets are thus protected.

J is a cross-beam or casting of the form in cross-section shown at Fig. 1, having its ends walled in similarly to the cross-beam C, and said beam J and cross-beam D serve as supports for the lower and upper ends, respectively, of the step-bar or rider K, upon which 75 rest the grate-bars L. The construction of these step-bars K is most clearly shown at Fig. 3, from the inspection of which it will be seen that the upper ends of the bars are cast with 80 lateral projections M, adapted to ride upon the cross-bar or support D, and the lower ends with right-angle spaces or shoulders 85 adapted to fit and ride upon the upper tread of the cross-bar or casting J. The upper or inclined edge of the bars K are formed with a series of steps, N, upon which the grate-bars 90 L are placed, and for the purpose of giving a broader bearing to the grate-bars the steps N are extended beyond the body K or web, the rear edge of which is curved, as shown. The longitudinal bottom grate-bars, O, rest upon the lower step or projection of the cross-bar J and a cross-bar, P, built in the fire-bridge.

The transverse or stepped grate-bars L are 100 constructed, as more particularly shown at Figs. 4, 5, 6, and 7, with air spaces or openings through the top to freely admit air, and having the under side formed with longitudi-

nal and transverse webs, as clearly shown at Figs. 5, 6, and 7, whereby great strength and protection against warping are secured.

It will be observed that by reason of the construction and arrangement of the stepped grate-bars air for combustion is admitted not only through but also between the bars, and this is an important desideratum in boiler-settings of the class referred to.

In addition to the improvements already described, I arrange in the fire-bridge a cast-iron box-flue, Q, the peculiar construction of which will be best understood by reference to Fig. 8. The box is composed of top and sides, and, being open at the bottom, the exterior surfaces of this box are straight and practically smooth, with the exception of a projecting foot, R, at the bottom edge, which is built in the fire-brick which overlay the box, and in this way and by the lateral projections b the latter is held against any movement. The edges of the sides of the box rest upon the fire-brick forming the bottom of the flue. In order to protect the box Q against warping, the interior surface of the top is strengthened by longitudinal and transverse ribs a, which are

inclined from the center outward. The fire-brick placed over the box Q protect the box from the direct heat of the fire; but sufficient radial heat is obtained to thoroughly heat any 30 currents of air admitted through the damper S (arranged in the vertical front of the bridge-wall, as clearly seen at Fig. 1) in its passage through the flue and before it reaches the combustion-chamber.

What I claim as new, and desire to secure by Letters Patent, is—

The heating-flue box Q, constructed of cast-iron, open at the bottom, and provided with the foot R, and flanges b, for securing the box 40 in place in the fire-bridge, and strengthened by the longitudinal and transverse ribs a, inclined from the center outwardly, said flue-box being arranged within the fire-bridge, substantially as hereinbefore set forth. 45

In testimony whereof I have hereunto set my hand and seal in the presence of two subscribing witnesses.

W. T. HILDRUP, JR. [L. S.]
